UNITED STATES PATENT OFFICE.

DE WITT TOWER, OF SPENCER, MASSACHUSETTS.

JAR-OPENER.

1,357,914.

Specification of Letters Patent.

Patented Nov. 2, 1920.

Application filed March 5, 1919. Serial No. 280,769.

To all whom it may concern:

Be it known that I, DE WITT TOWER, a citizen of the United States, residing at Spencer, in the county of Worcester and State of Massachusetts, have invented a new and useful Jar-Opener, of which the following is a specification.

This invention relates to a device for raising the covers of glass topped fruit jars of the so-called "Lightning" type for example, and the principal object thereof is to provide a device of extreme simplicity which will avoid the common fault of fruit jar openers, namely the application of the pressure to a single point. By distributing the pressure substantially all the way around I avoid the common fault of tending to break the glass cover or jar. Another object of the invention is to provide a construction which without adjustment is capable of use for all such jars of ordinary sizes and can be used independently of the particular make and design thereof; and especially to provide a device which can be made of only two parts if desired and will involve very little expense in manufacture.

Further objects and advantages of the invention will appear hereinafter.

Reference is to be had to the accompanying drawings, in which—

Figure 1 is a plan of a part of a jar with a preferred embodiment of this invention applied thereto;

Fig. 2 is a similar view showing the parts in the position assumed when turned far enough to raise the cover;

Fig. 3 is a sectional view on the line 3—3 of Fig. 2 showing the parts in the same position, and

Figs. 4 and 5 are plans of modified forms coming within the scope of this invention.

So far as I am aware it has been the universal fault of all openers for glass topped jars of the type specified that they applied the pressure at a single point or at two diametrically opposite points, thus concentrating the pressure and tending to break or crack the cover or jar. I am aware of the fact that devices have been provided in which a band extends around the jar or cover for the purpose of providing a support for a single cutting edge or wedge

which necessarily has the above mentioned defect because all the force is concentrated at one point.

My invention at first sight appears similar to jar openers of that type because I provide a band which extends around the jar and pivot to it a handle which is tilted to open the jar. However my invention involves fundamental differences over the above mentioned type of jar opener for instead of using the band to support a lever and cutting edge I use the band solely for the purpose of acting as a wedge itself and applying the pressure substantially all the way around the circumference of the jar directly under the edge of the cover so as to raise the cover without applying any more pressure at one point than at another. In fact the use of a wedge attached directly to the tilting handle is entirely done away with by my invention, except that the surrounding wire itself is used for that purpose, but it is used in a very different way and has a very different result as will appear. It is to be distinctly understood that this invention is not in any sense a wrench and is incapable of effective use for unscrewing the Mason screw cover or any other cover of that type.

Referring particularly to the drawings it will be seen that I have shown the invention in the first three figures as applied to a well-known type of glass jar. In this form of the invention it comprises a handle 10 with an integral flange 11 at one end, this flange having a convex surface 12 adapted to engage with the upper part of the jar and with the cover. In other words it bridges the space between the jar and cover and bears on both of them when put in place for operation. This element 10 and 11 is merely a handle and abutment, the handle serving as a lever with the abutment as its fulcrum. It has no sharp edge and although the flange 11 comes against the edge of the jar and cover its pressure is distributed between the two and exerted in the plane of the top of the jar and it cannot apply in any way a pressure to the cover to raise it.

The latter function is accomplished by the use of a flexible member 13 which extends around the jar at the top preferably over

the packing ring and just under the inwardly slanting lower edge of the cover. This flexible member is made of such a form as to exert a wedging action on the bottom 5 of the cover when drawn in between it and the supporting ledge on the jar below it. This can be accomplished by giving it a special shape if desired, but I find in practice that an ordinary wire of circular cross 10 section furnishes all the wedging action that is desired.

From a comparison of Figs. 1 and 2 it will be seen that the flexible wire member 13 is simply placed over the cover and brought down into proper position as described above, so that the flange 11 bears on the cover and jar and then the handle 10 is turned in either direction from the normal 20 until the wire 13 is forced inwardly all around far enough to lift the cover as shown in Figs 2 and 3, and let the air under. In this way it will be observed that the cover is raised by pressure exerted equally on substantially the entire circumference 25 of its lower edge and no point on this circumference gets an excess of pressure. Therefore no opportunity is provided for breaking or cracking it. Likewise the pressure on the top ledge of the jar is distributed 30 equally, and I have found in practice that the breaking of these glass parts is entirely avoided by this device.

This is a departure from the nearest types 35 of jar openers with which I am familiar. Although some of them involve bands extending around the jar or cover for supporting a separate wedge or knife edge, they always depend on the latter for opening the jar. The wedge is depended on either to 40 lift the cover or to penetrate over the rubber packing ring and let air into the jar. Apparently it has been thought heretofore that it was advantageous to apply the pressure all at one point because it is obviously necessary only to let air in at a single point 45 in order to relieve the cover from atmospheric pressure which holds it in place. It is obvious, however, that as the jar cover is rigid and not flexible there is no possibility of raising it at one point without tilting 50 it on its diametrically opposite edge and releasing it all the way around. Therefore the exertion of the pressure at one point is the wrong principle. The pressure should 55 be exerted practically all the way around the cover. The principal advantage in this invention lies in the fact that by the distribution of the pressure in this manner the possibility of breaking the cover or jar is 60 practically entirely avoided for reasons which have been stated above.

Another important advantage of this invention lies in the fact that without adjustment of the wire 13 the device can be ap-

plied to jars of smaller sizes than the one 65 shown, merely by swinging the handle 10 farther around. In other words a single implement is suitable for application to jars of all ordinary sizes. But I do not limit myself to the avoidance of adjustment. 70

Although the form shown in Figs. 1, 2 and 3 has proved to be satisfactory for the desired purpose I find that other forms can be used and in Fig. 4 I have shown a form involving a handle 20 rigidly connected 75 with a cylinder 21 which in this case I have shown as flat and continuous with the handle on top. The ends of the band 13 extend through the cylinder and their ends secured. This cylindrical member 21 then 80 serves as the abutment or fulcrum of the lever as in the other case.

In Fig. 5 I have shown a handle or lever 85 30 with an extension 32 at an angle to it. One end of the wire 13 is pivoted to a stud 33 on the end of this extension and the other end to a stud on the elbow formed between the two parts 30 and 32. This is a still simpler construction of handle, as in this 90 form I intend the member 30—32 to be a flat piece of metal not necessarily bridging the space between the jar and cover as in the other two cases, although that principle can be used with this form if desired. But if it is not used then the end of the part 95 32 will necessarily come in contact with the cover and it can be separated in the same way as described above. By pivoting the ends of the wire it is made more durable. This feature can be employed in connection 100 with the other forms.

Although I have illustrated and described only three forms of the invention I am aware of the fact that other modifications can be made therein by any person skilled 105 in the art without departing from the scope of the invention as expressed in the claims. Therefore I do not wish to be limited to all the details of construction herein shown and described but what I do claim is:— 110

1. In a jar opener, the combination with a smooth flexible wire adapted to surround a jar between the top thereof and the lower edge of the cover and convex means connected with both ends of said wire at one side and having a material thickness to prevent it from entering between the jar and the cover and adapt it for rolling on the exterior surface of the jar or cover, above or below the packing rubber and drawing both 115 ends of the wire simultaneously toward each other circumferentially and forcing the entire wire under the cover substantially all the way around to act as a circumferential continuous wedge and raise it from the 120 jar without turning the cover. 125

2. As an article of manufacture, a jar opener consisting of a rigid handle and a

flexible wire connection adapted to surround the jar below the cover thereof and entering the space between the top of the jar and the cover, said handle having on the 5 end thereof a convex surface or abutment extending substantially both above and below the flexible connection in position to en-

gage the edge of the jar and the edge of the cover on opposite sides of the flexible connection and to roll on said surfaces. 10

In testimony whereof I have hereunto affixed my signature.

DE WITT TOWER.
